UNITED STATES PATENT OFFICE.

WILLIAM KAUTT, OF ST. PAUL, MINNESOTA.

DESIGN FOR A WAGON-SKEIN.

54,632.

Specification for Design.

Patented Mar. 9, 1920.

Application filed May 24, 1917. Serial No. 170,760. Term of patent 14 years.

To all whom it may concern:

Be it known that I, WILLIAM KAUTT, a citizen of the United States, residing at St. Paul, county of Ramsey, and State of Minnesota, have invented a new, original, and ornamental Design for Wagon-Skeins, of which the following is a specification, reference being had to the accompanying drawings, forming part thereof.

Figure 1 is a side elevation of a wagon skein, showing my new design.

Fig. 2 is a plan view thereof.

Fig. 3 is an end view of the skein as seen from the left end of Fig. 1.

Fig. 4 is a cross section taken on the line 4—4 of Fig. 2 of my design.

I claim:

The design for a wagon skein as shown.

WILLIAM KAUTT.
